(57) **CLAIM**

The ornamental design for a article of jewelry, as shown and described.

DESCRIPTION

FIG. 1 is a front side perspective view of the article of jewelry.

FIG. 2 is a front elevation view thereof, the rear elevation view being a mirror image thereof.

FIG. 3 is a left side elevation view thereof, the right side elevation view being a mirror image thereof.

FIG. 4 is a top plan view thereof.

FIG. 5 is a bottom plan view thereof.

FIG. 6 is a top perspective view thereof; and,

FIG. 7 is a bottom perspective view thereof.

The broken lines in the drawings illustrate portions of the article of jewelry that form no part of the claimed design.

1 Claim, 6 Drawing Sheets
